Primary Examiner — Susan Moon Lee

(57) **CLAIM**

The ornamental design for a tamper-indicating box as shown and described.

DESCRIPTION

FIG. 1 is a perspective view of a tamper-indicating box, in accordance with the present design;
 FIG. 2 is a right side view thereof;
 FIG. 3 is a left view thereof;
 FIG. 4 is a rear view thereof;
 FIG. 5 is a front view thereof;
 FIG. 6 is a top view thereof;
 FIG. 7 is a bottom view thereof;
 FIG. 8 is a perspective view of a tamper-indicating box, according to a second embodiment;
 FIG. 9 is a right side view thereof;
 FIG. 10 is a left view thereof;
 FIG. 11 is a rear view thereof;
 FIG. 12 is a front view thereof;
 FIG. 13 is a top view thereof; and,
 FIG. 14 is a bottom view thereof.

1 Claim, 8 Drawing Sheets
